(57) **CLAIM**

The ornamental design for a sweep for cultivating soil in a field, as shown and described.

DESCRIPTION

FIG. 1 is a right-side perspective view of a sweep for cultivating soil in a field showing my new design.

FIG. 2 is a front view of the sweep of FIG. 1.

FIG. 3 is a rear view of the sweep of FIG. 1.

FIG. 4 is a right-side of the sweep of FIG. 1.

FIG. 5 is a left side of the sweep of FIG. 1.

FIG. 6 is a top view of the sweep of FIG. 1; and,

FIG. 7 is a bottom view of the sweep of FIG. 1.

1 Claim, 6 Drawing Sheets
